Patented Nov. 6, 1917.

UNITED STATES PATENT OFFICE.

ROY V. PEPPERBERG, OF LINCOLN, NEBRASKA.

NOVELTY-BOX.

1,245,378.

Specification of Letters Patent.

Patented Nov. 6, 1917.

Application filed December 15, 1915. Serial No. 67,040.

To all whom it may concern:

Be it known that I, Roy V. PEPPERBERG, residing at Lincoln, in the county of Lancaster and State of Nebraska, have invented 5 a new and Improved Novelty-Box, of which the following is a specification.

This invention, which in its generic nature has reference to improvements in cigar boxes, is more especially intended to serve the purpose of providing a novelty packing differing from the ordinary cigar packing, in that the top row contains but a single cigar held in a specially made tray of the thickness of a cigar and provided with a groove or open 15 ended pocket into which one cigar may be inserted (or more, if desired,) the tray being of a depth of the thickness of a cigar and serving as a filler for the top of the box and adapted for resting upon the top row 20 of the cigars contained within the box.

My invention also has for its object to provide a cigar box which in addition to serving the usual function is in the nature of an advertising novelty since the same presents special selling features. 25

With other objects in view that will hereinafter appear, my invention is a novelty box for packing cigars that embodies the peculiar features of construction and arrangement of parts hereinafter described, 30 specifically pointed out in the claims and illustrated in the accompanying drawings in which:

Figure 1 is a perspective view of a novelty 35 box that embodies my improvements, the box being shown as closed.

Fig. 2 is a similar view thereof, the box lid being opened.

Fig. 3 is a perspective view that illustrates the manner in which the tray member 40 is lifted out of the box.

Fig. 4 is a transverse section of the box taken substantially on the line 4—4 of Fig. 1.

Fig. 5 is a perspective view of the tray 45 member.

In carrying out my invention, the box member is of the usual formation except that its depth is increased the thickness of a cigar to accommodate a tray or supplemental holder, presently again referred to, and which, when packed rests upon the top 50 of the packed rows of cigars contained within the box.

In the drawing, (see Fig. 4) I have shown 55 a box 1 adapted for containing 25 cigars which, in my improved box, are packed in

four rows of six in each row, and the single or 25th cigar is held in the tray which fills the space between the top row of the cigars and the box lid 2, the latter being preferably 60 hinged at one end 20 to swing up to the open position, as shown in Fig. 2, a suitable catching device 3 being attached to the front end of the box for holding the lid closed.

The tray 4 has a groove or pocket 40 that 65 preferably extends diagonally of the box thereby providing a pocket somewhat longer than the cigar to be held therein, and to prevent the cigar from accidentally sliding endwise out of the groove when lifting the tray 70 from the box in the manner shown in Fig. 3.

The tray 4 may be of any suitable light weight material, preferably paste-board bent up to a shape to snugly fit within the upper end of the box, as is best shown in Fig. 4 by 75 reference to which it will be noticed that the tray, when in position seats upon a lifting member 5, one end of which is nearly the length of the box and is fastened to one side thereof. The member 5 terminates in a pull 80 tab 50, the end 51 of which projects outside of the box and may be left projected when the lid is down, if so desired.

From the foregoing taken in connection with the drawings, the complete formation 85 and the manner of use of my improved novelty box will be readily apparent.

By reason of providing a tray adapted to be fitted within the top of the box over the packed rows of the cigars and having a 90 pocket to receive a single cigar (or more if desired), the odd cigar is neatly held in the tray and the latter with the cigar may be conveniently and quickly lifted out on the box by raising the tray in the manner stated 95 and as indicated in Fig. 3 of the drawing.

The tray feature adds a new, novel and special selling feature in cigar packing and so far as I know is new to the trade, and the same may be also utilized as an advertising 100 medium by printing or otherwise applying the brand or label for the particular cigar on the tray.

To hold the cigar from sliding diagonally in the groove of the holder, it is wrapped in 105 a silver foil, the opposite ends of which are twisted to form puffs or lateral enlargements 41 that tend to frictionally engage the sides of the groove, and thereby hold the cigar from sliding endwise in the groove when 110 lifting the holder out of the box.

The pull tab is normally turned back onto

the holder when the box lid is down, as is clearly shown in Fig. 4.

It should be noted that the tab 51 is folded back between the tray and the lid 5 when the box is closed for shipment (see Fig. 4) but it may be left projected as shown in Fig. 2 when the lid is opened for display or closed simply temporarily.

What I claim is:

- 10 1. In combination with a cigar box, a removable display filler tray located in the box and having a diagonal pocket to receive and display a cigar.
- 15 2. In a packing box of the character stated, a supplemental holder having a pocket for holding at least one sample cigar, the said holder being supported on top of the packed cigars within the box to form a filler for that part of the box between the packed articles and the lid, a flexible pull member 20 that extends across the box and is located between the filler and the packed articles within the box, one end of said member being fixedly attached to one side of the box, the other end of said member being free and terminating in a pull flap adapted to be opened up and extended over the other side of the box when the lid of the box is opened and adapted to be bent back upon itself to lie between the filler and the lid when the lid is closed.
- 25 3. The combination with a box having a lid; of a removable tray that snugly fits in the top of the box to rest on the articles packed therein, said tray having a pocket for holding at least one of the articles such
- 30
- 35

as are packed in the box, said pocket extending diagonally of the tray.

4. The combination with a box having a lid; of a removable tray that snugly fits in the top of the box to rest on the articles packed therein, said tray having a pocket for holding at least one of the articles such as are packed in the box, and means attached to the box for lifting the said tray out of the box. 45

5. The combination with a box having a lid; of a removable tray that snugly fits in the top of the box to rest on the articles packed therein, said tray having a pocket for holding at least one of the articles such as are packed in the box, means attached to the box for lifting the said tray out of the box, said means consisting of a flexible member secured at one end to one side of the box and extending across the box under the tray 50 and having its free end adapted for being projected over the box edge to form a pulling tab. 55

6. As a new article, a cigar box having a lid, a flexible member secured at one end to one side of the box, and extended across the box and having its free end projected over the other side of the box and terminating in a pulling tab, and a tray adapted to be removably mounted in the other end of the box to rest on the top of the articles in the box and on the lifting member, said tray having a pocket for holding at least one of the articles such as are packed in the box. 65

ROY V. PEPPERBERG.
